KITCHEN CABINET INCINERATOR

Guyon L. C. Earle, Forest Hills, N. Y.

Application May 5, 1947, Serial No. 746,119

11 Claims. (Cl. 110—18)

1

This invention relates to incinerators and more specifically to an incinerator which is adapted to form a part of a utility or kitchen unit.

It is an object of this invention to provide an incinerator which forms one of the component parts of a utility or kitchen unit.

In a copending application of the present inventor, Serial No. 629,680, filed November 19, 1945, which application is now abandoned, there is disclosed a utility unit of the "set-back" or L-shaped type. This unit has a lower portion including the lower part of a space heater and a clothes washer and a deep freeze unit, an intermediate portion including another part of the space heater and cabinet space, and an upper portion enclosing the upper part of the space heater and its accompanying flue pipes and having, in addition, storage space. A long table-top member is located on top of the lower portion and in front of the intermediate portion of the utility unit. The present invention, in one of its primary aspects, relates to the utilization of a portion of the cabinet space in the intermediate and upper portions of the utility unit for incinerating purposes.

In another of its aspects, the invention relates to the utilization of space above and behind other units of the setback type, such as stoves and cabinet units for example, for incinerating purposes.

It is another object of this invention to provide an incinerator occupying the intermediate and upper portions of an L-shaped or "set-back" utility or kitchen unit.

It is still another object of this invention to provide a simple, convenient and cheap incinerator which matches in appearance other elements of a kitchen or utility unit.

It is a further object of this invention to provide a utility unit having as elements thereof a house or space heater, an incinerator adjacent thereto and a common flue system for the heater and the incinerator.

It is still another object of this invention to provide a novel combined incinerator and table-top unit.

These and related objects are attained in accordance with the invention by providing, as an illustrative embodiment thereof, a utility unit of the L-shaped or set-back type (that is, one in which the front of the intermediate portion thereof and the front of the upper portion thereof are placed to the rear (or "set-back" from) the front of the lower portion of the unit) having a table-top member above the lower portion and in front of the intermediate portion and including in the

2

intermediate and upper portions of the unit an incinerator. The incinerator has a flue system which may connect with that of the space heater if the utility unit includes one. The incinerator is provided with three doors, a feed door, a combustion chamber door and a clean-out door. The feed door is located in the lower part of the upper portion of the utility unit and is hidden by the upper cabinet door while the combustion chamber door and the clean-out door are hidden by an access door located in the intermediate portion of the unit immediately above the table-top member which provides a convenient resting place for refuse, garbage, etc., prior to and while it is being placed in the incinerator.

The invention will be more readily understood by referring to the following description taken in connection with the accompanying drawings forming a part thereof, in which:

20 Fig. 1 is a perspective view of an L-shaped or "set-back" utility unit in accordance with the invention including an incinerator in the intermediate and upper portions thereof;

25 Fig. 2 is an enlarged cross-sectional view of the operating portion of an incinerator unit;

Fig. 3 is a perspective view of an incinerator unit in which the lower portion thereof houses a clothes washing machine;

30 Fig. 4 is a perspective view of an incinerator unit in which the lower portion thereof comprises a stove; and

35 Fig. 5 is a perspective view of an incinerator unit in which the lower portion thereof comprises shelved or drawer cabinet space, the access doors to the incinerator being on the side rather than the front of the unit.

Referring more specifically to the drawings, Fig. 1 shows, by way of example and in perspective, a utility unit 10 in accordance with the invention including an incinerator unit 11 of novel arrangement. The utility unit 10 is of the L-shaped or "set-back" type, that is one in which the front of the intermediate portion 12 thereof and the front of the upper portion 13 thereof are placed to the rear of the front of the lower portion 14 of the unit. The lower portion 14 comprises the lower part 15 of a space heater, a clothes washer 16, and all or the lower portion 17 of a deep freeze unit. The intermediate portion 12 of the unit 10 comprises the intermediate portion 18 of the space heater, the intermediate portion 19 of the incinerator unit 11, and a cabinet or the upper portion 20 of the deep freeze unit. The upper portion 13 of the unit 10 comprises the upper portion 21 of the space heater, the upper por-

40

45

55

tion 22 of the incinerator unit, and shelved cabinet space 23. A table-top member 24 is placed above the lower portion 14 and in front of the intermediate portion 12 and has openings therein for the soap hole 25 of the clothes washer and access door 26 for the deep freeze unit. The whole unit 10 preferably rests on a recessed base 27. A complete utility unit of the type briefly described above, except that a cabinet replaces the incinerator portions 19 and 22, is disclosed in the above-identified Earle application.

Referring now to Figs. 2 to 5 inclusive, in addition to Fig. 1, the incinerator unit 11 includes a lower portion which may be a clothes washer 16 as in Figs. 1 and 3, a stove 28 as in Fig. 4 or 15 shelved or drawer cabinet space 29 as in Fig. 5, and intermediate and upper portions 19 and 22, respectively, which are shown in Fig. 2 regardless of the type of lower portion used.

In the intermediate portion 19 is positioned a 20 combustion chamber 30 above a gas, electric or liquid fuel burner 31 suitable for oil or gas operation. In the combustion chamber there is placed a wire mesh basket 32 for holding the garbage, paper, etc. being consumed. This refuse is fed into the incinerator by means of the feed door 33 into the insulated feed hopper 34 above the basket 32. The basket 32 rests on supporting members 35 and can be easily removed for 25 cleaning or replacement. The heat and smoke goes up the stack or flue 36 which can, if desired, connect with the flue 31 of the house or 30 space heater, as shown in Fig. 1. The flue 36 passes up through a shelved cabinet member 38 above the hopper 34. Access to the combustion 35 chamber to light the burner 31 or for cleaning purposes is obtained by means of the combustion chamber door 41. Below this door is a clean-out door 42 through which ashes, dirt, etc. can be removed. This door 42 is conveniently placed just above the table-top member 24 so that in order to clean out the incinerator it is only necessary to spread a piece of newspaper, for example, on the table-top member 24 and scrape the ashes into it. This is a great improvement over the usual wall incinerator where a receptacle must be held up close to the clean-out door and the ashes swept into it or into a dustpan which rests on the floor (requiring stooping to clean out the incinerator). The table-top member 24 also serves as a convenient means of supporting refuse as it is being put into the incinerator through the door 33.

An outer door 39 covers both doors 41 and 42 and another outer door 40 covers the door 33 and also the shelved cabinet space 38. The outer doors 39 and 40 can be given the same appearance as corresponding doors in the other elements of the utility unit 10 for greater ornamental beauty of the unit 10 as a whole. If desired the door 40 can be omitted (as in Figs. 3, 4 and 5) especially when the shelved cabinet space 38 is not furnished with or associated with the incinerator unit. If desired, both doors 41 and 42 can be omitted and the single door 39 used alone. The double door arrangement is preferred, however, for greater cleanliness, beauty and for insulation purposes. The door 40 in Fig. 2 can be in two parts hinged at the sides and opening and closing at the center; as shown in Fig. 1. When the incinerator forms part of a unit, the outer doors 40 and 39 are given the same curvature as other doors in the same respective portions of the unit, as indicated in Fig. 1.

The incinerator of this invention may be a part of a utility unit (as in Fig. 1), as a part of a kitchen unit, or furnished as a separate unit using any desired appliance or cabinet in the lower unit. The various doors 33, 39, 40, 41 and 42 may be at the front (as shown in Figs. 1 to 4, inclusive), or at the side (as shown in Fig. 5). Moreover, some of these doors may be at the front and some at the side.

Various other modifications can be made in the embodiments described above without departing from the spirit of the invention, the scope of which is indicated in the appended claims.

What is claimed is:

1. An insulated L-shaped or set-back incinerator unit comprising a lower portion, an intermediate portion and an upper portion, the front of the intermediate portion and the front of the upper portion being positioned to the rear of the front of the lower portion, a horizontal table-top member above the lower portion and in front of the intermediate portion, a combustion chamber and an ash receptacle in said intermediate portion, an insulated feed hopper in said upper portion communicating at its lower end with the upper portion of the combustion chamber for the feeding of matter to be incinerated, and a flue connected to said hopper, said ash receptacle being located below the combustion chamber and in communication therewith for the transfer of ashes from said combustion chamber to the ash receptacle.

2. The combination of elements as in claim 1 and in which said flue comprises a vertical pipe section in said upper portion.

3. The combination of elements as in claim 1 in further combination with a combustion chamber door in the intermediate portion communicating with the combustion chamber and a clean-out door in the intermediate portion communicating with the ash receptacle.

4. The combination of elements as in claim 1 in further combination with a combustion chamber door in the intermediate portion communicating with the combustion chamber and a clean-out door in the intermediate portion communicating with the ash receptacle, said doors being at the front of said unit.

5. The combination of elements as in claim 1 in further combination with a combustion chamber door in the intermediate portion communicating with the combustion chamber and a clean-out door in the intermediate portion communicating with the ash receptacle, said doors being at the side of said unit.

6. The combination of elements as in claim 1 in further combination with a combustion chamber door in the intermediate portion communicating with the combustion chamber and a clean-out door in the intermediate portion communicating with the ash receptacle and located only slightly above said table-top member whereby said incinerator can be easily cleaned.

7. The combination of elements as in claim 1 in further combination with a combustion chamber door in the intermediate portion communicating with the combustion chamber, a clean-out door in the intermediate portion communicating with the ash receptacle, and an outer door covering said combustion chamber and clean-out doors.

8. The combination of elements as in claim 1 in further combination with a feed door for said hopper and communicating therewith.

9. The combination of elements as in claim 1 in further combination with a feed door for said hopper and communicating therewith, said feed door being at the front of said unit.

10. The combination of elements as in claim 1 in further combination with a feed door for said hopper and communicating therewith, said feed door being at the side of said unit.

11. The combination of elements as in claim 1 in further combination with a feed door for said hopper and communicating therewith and an outer door covering said feed door.
